UNITED STATES PATENT OFFICE.

ROBERT E. WOODS AND JAMES D. WATKINS, OF PORTERVILLE, CALIFORNIA.

ELECTRIC HEATER.

Application filed October 20, 1925. Serial No. 63,707.

This invention relates to improvements in heaters, and has for its principal object to provide a highly simple and novel means for heating air which circulates upwardly 5 through the heater.

One of the important objects of the present invention is to provide an electric heater which is of such construction as to permit the same to be placed in any desirable place 10 in a room for the purpose of heating the air therein at a low temperature.

A further object is to provide an electric heater of the above mentioned character which is simple in construction, inexpensive, 15 and furthermore adapted to the purposes for which the same is designed.

Other objects and advantages of this invention will become apparent during the course of the following description.

20 In the accompanying drawing forming part of this specification and in which like numerals are employed to designate like parts throughout the same:—

Figure 1 is a top plan view of the electric heater embodying our invention,

Fig. 2 is a vertical sectional view taken approximately on line 2—2 of Fig. 1, and

Fig. 3 is a front elevation of the heater element supporting means.

30 In the drawing wherein for the purpose of illustration is shown the preferred embodiment of our invention, the numeral 1 designates generally our improved electric heater, the same comprising a rectangular-shaped casing which includes the end members 2, the side walls 3 and the top or cover 4. The top is provided with downwardly extending flanges 5 at its respective edges so as to permit the same to fit over the 40 upper edges of the end and side walls respectively of the casing for further securing the cover in position on the top of the casing, suitable screws such as are shown at 6 may be employed.

5 The top or cover 4 is provided in its central portion or its intermediate portion with a series of closely arranged openings 7. A series of spaced openings 8 are also formed in the top or cover 4 adjacent the longitudinal side thereof and the purpose of these openings will be hereinafter more fully described.

The lower edges of the side walls 3 of the casing terminate at a point above the 50 lower edges of the end walls 2 in the manner as clearly shown in Fig. 2 to provide

an air inlet 9 at each side of the bottom of the casing. The bottom of each of the end walls 2 is also cut away as indicated at 10 to provide what we term as supporting 60 feet 11, whereby the heater may rest in a proper position on the floor.

A baffle plate 12 extends longitudinally within the lower portion of the casing, the ends of the baffle plate being secured to the 65 respective end walls of the casing in any suitable manner. As is clearly shown in Fig. 2, the longitudinal side edges of the baffle plate are spaced from the respective side walls of the casing so as not to interfere 70 with the circulation of air upwardly through the casing upon entering the latter at the entrance 9. The baffle plate is preferably located at a point adjacent the bottom edges of the side walls 3. 75

Extending longitudinally within the upper portion of the casing are partitions 13. In the present instance, two of such partitions are provided, the same extending between the ends 2 of the casing and are preferably arranged adjacent the respective sides of the casing. The upper edges of the partitions are disposed substantially flush with the upper edges of the side and end walls of the casing and the lower edges of the partitions terminate at a point above the lower edges of the side walls 3. These partitions thus provide a relatively large central compartment 14 and relatively narrow end compartments 15. The purpose of these compartments will be presently apparent. 85

A series of vertically arranged and parallel spaced metallic strips 16, have their upper and lower ends disposed laterally as clearly illustrated at 17 and 18 respectively. 95 The laterally disposed upper ends 17 are welded or otherwise secured to the bottom of the top or cover 4 in the intermediate portion thereof and adjacent the respective ends. 100

The laterally disposed lower ends 18 of each series of vertically arranged strips are secured to the cross strips 19 in the manner as clearly shown in Fig. 2. The cross strips provide a means for holding the lower ends 105 of the vertical strips in parallel spaced relation and these cross strips are of such length as to permit the same to be disposed within the central compartment 14.

Each of the vertically arranged strips 16 110 is provided with a series of openings 20 for permitting the respective ends of the elec-

tric heating elements designated generally by the numeral 21 to be attached thereto, the heating elements extending longitudinally within the central compartment 14 and transverse with respect to the vertical strips 16. As is clearly shown in Fig. 2, the heating elements are secured on the vertical strips 16 so as to have the heating elements on one pair of strips disposed in 10 staggered relation with respect to the heating elements carried by the adjacent pair of vertical strips. As the electric heating elements are all of any well known construction, a further detailed description 15 thereof is not thought necessary.

By attaching the electric heating element supporting means to the intermediate portion of the bottom of the top or cover 4, the same may be readily placed within or 20 moved from the central compartment 14.

With the parts arranged as shown in the drawing, it is obvious that cold air will enter the casing through the entrance 9 and will circulate upwardly thru the central 25 compartment 14 and the end compartment 15. It is of course understood that the electric heating elements or units 21 are connected to a suitable source of electric current in any well known manner and as 30 the air circulates upwardly through the casing, the same will become heated and will escape through the openings 7 and 8 provided in the top or cover 4 so as to cause a constant supply of heated air within the 35 room in which the electric heater is placed. For the purpose of facilitating the handling of the electric heater to further permit the same to be carried from place to place, suitable handles such as shown at 22 are attached to the end walls of the casing.

The provision of the partitions 13 and the end compartment 15 will prevent the side walls 3 of the casing from becoming excessively hot. Furthermore the provision 45 of the baffle plate 12 will prevent the downward reflection of the heat to further restrict the flow of incoming cold air into the central compartment 14. If desired, a pan 50 of water may be placed on the baffle plate to act as a humidifier. The pan is illustrated at 23 in Fig. 2 of the drawing.

The electric cord which leads from a suitable source of supply is adapted to extend through a suitable bushing 24 provided 55 therefor in one of the end walls of the casing and may be attached to the electric heating elements in any suitable manner.

It will thus be seen from the foregoing description, that an electric heater has been 60 provided which will permit the air to be heated at a low temperature very easily and efficiently and the simplicity in which our improved heater is constructed enables

the same to be easily handled and may be placed in any desirable place.

While we have shown the preferred embodiment of our invention, it is to be understood that various changes in the size, shape and arrangement of parts may be resorted to without departing from the spirit or sacrificing any of the advantages of the appended claims.

Having thus described our invention, what we claim as new is:—

1. An electric heater comprising a casing 75 including side and end walls, and a perforated top, the bottom of the side walls being spaced from the bottom of the end walls to provide a cold air inlet, longitudinally extending partitions having their ends 80 secured to the respective end walls of the casing, the lower edges of the partitions terminating at a point above the lower edges of the side walls of the casing, said partitions providing a central and end air 85 compartment, a series of vertically arranged strips secured at their upper ends to the intermediate portion of the perforated top adjacent the respective ends thereof, additional strips securing the lower ends of the 90 strips of each series, and heating elements 95 extending longitudinally within the central compartments and secured at their respective ends to the adjacent strips of each series, the heated air escaping through the perforations provided in the top of the casing.

2. An electric heater comprising a casing including side and end walls, and a perforated top, the bottom of the side walls being 100 opposed from the bottom of the end walls to provide a cold air inlet, longitudinally extending partitions having their ends secured to the respective end walls of the casing, the lower edges of the partitions terminating at 105 a point above the lower edges of the side walls of the casing, said partitions providing a central and end air compartment, a series of vertically arranged strips secured at their upper ends to the intermediate portion of the perforated top adjacent the respective ends thereof, additional strips 110 securing the lower ends of the strips of each series, and heating elements extending longitudinally within the central compartments and secured at their respective ends to the adjacent strips of each series, the heated air escaping through the perforations provided in the top of the casing, and a baffle plate extending longitudinally within 115 the lower portion of the casing at a point adjacent the lower edges of the side walls.

In testimony whereof we affix our signatures.

ROBERT E. WOODS.
JAMES D. WATKINS.
